COMBINED DRIER AND SPACE HEATER

Rallston M. Sherman, Glastonbury, Conn., assignor to
The Silent Glow Oil Burner Corporation, Hartford,
Conn., a corporation of Connecticut

Application June 29, 1956, Serial No. 42,090

Term of patent 14 years

(Cl. D81—1)

Des. 180,962

*Fig. 4.Fig. 6.Fig. 5.*Fig. 1 is a top plan view of a combined drier and space heater, showing my new design;

Fig. 2 is a front elevational view;

Fig. 3 is a rear elevational view;

Fig. 4 is an end elevational view from the left of Fig. 2;

Fig. 5 is an opposite end elevational view on a reduced scale; and

Fig. 6 is a sectional view, on a reduced scale, on the line 6—6 of Fig. 3.

I claim:

The ornamental design for a combined drier and space heater, substantially as shown.
